UNITED STATES PATENT OFFICE.

GEORGE J. GOODHUE, OF STEVENS POINT, ASSIGNOR OF ONE HALF TO
HARVEY M. WADLEIGH, OF HATLEY, WISCONSIN.

WOOD-WORKING MACHINE.

SPECIFICATION forming part of Letters Patent No. 374,672, dated December 13, 1887.

Application filed May 9, 1887. Serial No. 236,831. (No model.)

To all whom it may concern:

Be it known that I, GEORGE J. GOODHUE, of Stevens Point, in the county of Portage, and in the State of Wisconsin, have invented certain new and useful Improvements in Wood-Working Machines; and I do hereby declare that the following is a full, clear, and exact description thereof.

My invention relates to wood-working machines, being specially designed for beveling the ends of the caps that form part of the timber structure for mines, set forth in Letters Patent No. 358,261, dated February 22, 1887; and it consists in certain peculiarities of construction and combination of parts, to be hereinafter described with reference to the accompanying drawings and subsequently claimed.

In the drawings, Figure 1 represents a plan view of a machine constructed according to my invention; Fig. 2, a partial elevation of the same, and Fig. 3 a partial side view of a completed cap.

Referring by letter to the drawings, A A represent horizontal beams, each of which is provided with a track, B, for the wheel C of a carriage, that comprises two beams, D D, having oblique arms E E extending inwardly therefrom, said arms of one beam being adjustably secured upon those of the other, as illustrated in Figs. 1 and 2.

Secured to the upper face of each beam D is a plate, F, that has a flanged segmental inner edge, G, and fast on each plate is an angle-iron, H, the vertical portion of which is convex upon its inner face. The plates F serve as head-blocks, and are arranged to be on opposite sides of and equidistant from the center of the carriage.

Arranged on the mill-floor outside of each beam A are frames I, provided with bearings J for the arbors of circular saws K, and fast to each arbor is a drive-pulley, L.

When the timber to be operated upon is in position on the carriage, it lies at an angle of forty-five degrees to the plane of the saws K, and is retained in this position by the arc-shaped shoulders a and concave recesses b in its ends, respectively engaging the flanges G of the plates F and the vertical convex portions of the angle-irons H, secured to said plates, it being understood that the shoulders and recesses above mentioned have been made by another machine.

As the carriage is pushed along the timber comes into contact with the saws, and from each end of said timber, on opposite sides thereof, the same is cut away at an angle of forty-five degrees. The carriage is now run back, the timber canted over, and the above-described operation repeated to complete the beveling.

Having thus fully described my invention, what I claim as new, and desire to secure by Letters Patent, is—

1. In a wood-working machine, the combination of suitable saws, a carriage, and two head-blocks, respectively secured to each side beam of the carriage on opposite sides of and equidistant from the center thereof, whereby a timber in position to be operated upon will lie at an angle of forty-five degrees to the plane of the saws, substantially as set forth.

2. In a wood-working machine, the combination of suitable saws, a carriage, two head-blocks each comprising a plate secured to a side beam of the carriage and provided with a flanged segmental inner edge, and an angle-iron fast on the plate, and having a convex inner face upon its vertical portion, said head-blocks being respectively arranged on opposite sides of and equidistant from the center of said carriage, substantially as set forth.

3. In a wood-working machine, the combination, with suitable saws, of a carriage comprising two beams united by oblique arms, and head-blocks secured to the beams on opposite sides of and equidistant from the center of the carriage, substantially as and for the purpose set forth.

4. In a wood-working machine, the combination, with suitable saws, of a carriage comprising two beams having adjustably-united inwardly-extending oblique arms, and head-blocks secured to the beams on opposite sides of and equidistant from the center of the carriage, substantially as and for the purpose set forth.

In testimony that I claim the foregoing I have hereunto set my hand, at Milwaukee, in the county of Milwaukee and State of Wisconsin, in the presence of two witnesses.

GEORGE J. GOODHUE.
